GAME TABLE

Hans J. Seebeck, Cold Springs, Ky., assignor to Patterson International Corporation, Cincinnati, Ohio, a corporation of Ohio

Filed Aug. 23, 1965, Ser. No. 86,681

Term of patent 14 years

(Cl. D34—5)

Fig. 1

Fig. 2

Fig. 3

Fig. 4

FIGURE 5 is a detailed sectional view taken along the lines 5-5 of FIGURE 1, both of said sectional views being taken looking in the direction of the arrows at the end of the section line.

I claim:

The ornamental design for a game table, as shown.
